UNITED STATES PATENT OFFICE.

JOHN J. HOFFMAN, OF PITTSBURGH, PENNSYLVANIA, ASSIGNEE, BY MESNE ASSIGNMENTS, TO P. H. MURPHY COMPANY, OF PARNASSUS, PENNSYLVANIA, A CORPORATION OF PENNSYLVANIA.

CAR-ROOF.

1,086,915.

Specification of Letters Patent.

Patented Feb. 10, 1914.

Application filed April 28, 1913. Serial No. 764,046.

To all whom it may concern:

Be it known that I, JOHN J. HOFFMAN, a citizen of the United States, and a resident of the city of Pittsburgh, in the county of Allegheny and State of Pennsylvania, have invented a new and useful Improvement in Car-Roofs, of which the following is a specification.

This invention relates to car roofs and 10 more particularly to outside metal roofs.

It has for its principal objects to produce a waterproof interlocking side seam or joint for the roof sheets which is sufficiently flexible and resilient to permit movement of the 15 roof sheets to compensate for the weaving and racking motion of the substructure; and to attain certain advantages which will hereinafter more fully appear.

The invention consists in the parts and 20 in the arrangements and combinations of parts hereinafter described and claimed.

In the accompanying drawing, which forms part of this specification, and wherein like symbols refer to like parts wherever 25 they occur, Figure 1 is a top plan view of a roof sheet having its side marginal portions arranged according to the invention; Fig. 2 is a longitudinal section of the eaves end portion of a roof sheet and a side view 30 of the ridge end portion of another sheet, illustrating the relative arrangement of the respective marginal seam portions which are adapted for slidable interlocking engagement; Fig. 3 is a section on the line 35 3—3 of Fig. 1; Fig. 4 is a section through the seam; and Fig. 5 is an end view showing a modification of the seam.

The roof sheets 1 may be arranged in any 40 desirable manner at the eaves ends thereof.

Said sheets may be adapted for a radial or curved arched roof and extend continuously across the car from eaves to eaves, or, as shown in the drawings, they may be of the type adapted for a ridge roof and extend 45 only from the eaves to the ridge.

The ridge end portion of the sheet illustrated is flanged upward, as at 2, and rebent outward and downward, as at 3, and the eaves end portion of the sheet is turned under and spaced from the body portion, as at 50 4; but, obviously, the ridge and eaves end formation may be varied at pleasure as the

specific form and arrangement constitutes no particular part of the present invention.

One of the side margins of the sheet shown 55 in Figs. 1 to 4, inclusive, is flanged upward, as at 5, and rebent inward and downward, as at 6, said portion 6 terminating some distance above the body of the sheet and being spaced from the upstanding portion 5; and 60 said portion 6 may either hang parallel with said portion 5 or be inclined away from it, as shown. The opposite marginal portion of the sheet is flanged upward, as at 7, and rebent outward and downward, as at 8. It 65 is again rebent inward and upward, as at 9, and then rebent back upon said portion 9, as at 10, thus producing an upstanding tongue comprising a double thickness of the metal; said tongue being bent over close to 70 the portion 8 so as to normally contact therewith or at least provide a restricted throat 11 corresponding approximately to and preferably less than the thickness of the metal sheet. The edge portion of this tongue is 75 preferably curved correspondingly to the bend of the metal between the portions 5 and 6 of the opposite margin of the sheet; and the tongue terminates nearly midway between the portions 7 and 8, as at 12.

In assembling the sheets on the roof they are slid endwise into engagement. That is, the marginal portion 6 of the one sheet is slipped between the portion 8 and tongue 9, 10, of the adjoining sheet, said portion 6 being thereby clamped in the region of the bend which connects it with the upstanding portion 5. By this arrangement a normally tight joint is had, yet there is sufficient flexibility and resiliency in the metal 80 to permit movement of the sheets so as to compensate for the motion of the substructure.

Preferably the height of the bend between the portions 5 and 6 is such that the adjacent body portion of the sheet is supported by the tongue 9, 10, of the adjoining sheet a slight distance above the substructure, thereby further insuring a contact with the tongue in the event it is sprung so far away 85 from the part 8 that the portion 6 will not be clamped. So, too, by this arrangement, there is a pivotal connection between the marginal portions of the two adjoining 90 100

sheets which permits considerable movement of the sheets without any appreciable distortion of the seam portions. It is also preferable to extend the free marginal portion of the sheet outward and downward from the portion 10, as at 13, the edge of said portion 13 terminating in a plane not higher than the body of the sheet, so as to provide a flange or lip which is adapted to bear upon the top face of the adjoining sheet. That is, said lip 13 is bent down at such an inclination that when the sheets are assembled, the lip is in constant contact with the adjoining sheet, even when the sheets are in movement. In this way the contact is also constant in the region of the margin of the upstanding tongue. Hence it is practically impossible for any water to be driven, even forcibly, between the lip 13 and the body of the sheet; and if any water should get under the lip 13 and into the space 14 between the flange 5 and tongue 9, 10, the area of said space is so much greater than the opening through which the water entered, that the water will be readily conducted off.

If the water should back up in the space 14, it is not liable to seep between the portion 6 and contacting tongue 9, 10; but in case any water does get by this point, the quantity will be small and it still has to pass around the edge of the portion 6 and up between said portions 6 and 8 where its flow is again blocked owing to the close contact of the portions 6 and 8 near the top of the seam. Hence, the water will be conducted off in the gutter provided by the space 15 in the region of the margin of said portion 6. Therefore, leakage is prevented, as it is practically impossible for water to reach the space 15 or at least not beyond it, even under most severe service conditions.

In order to facilitate joining the sheets, the marginal portions 7 and 8 at the ridge end are cut back in the region of the bend between them, as at 16, the end of the portion 8 being inclined, as at 17, to the bend where the tongue 9, 10, starts. The adjacent end portion 18 of the tongue is therefore uncovered as shown more clearly in Figs. 1 and 2, the corner 19 of the tongue being preferably rounded or beveled. It is also preferable to round or bevel the corner 20 at the eaves end of the downturned marginal portion 6 of the sheet. By this arrangement, in assembling the sheets, the ridge end of the downturned marginal portion of the one sheet is brought in close proximity to the eaves end of the inturned marginal portion of the sheet to be joined therewith. As the sheets are brought endwise together, the downturned portion 6 of the one sheet is made to overlap the exposed end portion 18 of the tongue 9, 10, of the other sheet and pressed against it. The tongue may thus be

pressed away from the portion 8 and the sheets easily slid into engagement, the rounding or beveling of the corners 19 and 20 of the sheets facilitating the initial engagement.

In the modification shown in Fig. 5 of the drawing, the underlying margin of the one sheet is turned up, as at 5^a, similarly to part 5 of the structure hereinbefore described, but the downturned portion 6 terminates in a plane much higher than the portion 6. The overlying marginal portion of the adjoining sheet is turned up, as at 7^a, then outward and downward, as at 8^a, whence it is bent outward and rebent, as at 13^a, to provide a flange or lip whose function is the same as the portion 13 in the other structure. The extreme marginal portion is then struck up close to the portion 8^a, as at 9^a, and preferably rebent, as at 10^a, thereby providing a tongue similar to the tongue 9, 10. In this modification, the portion 6^a is slipped between the tongue 9^a and portion 8^a and thereby clamped or supported, while the flange or lip 13^a presses on the adjacent body portion of the adjoining sheet; the only feature lacking being the gutter or space 15 of the structure herein first set forth. However, the shortness of the downturned portion 6^a and the space between the portion 5^a and the portion 7^a and tongue 9^a and the resilience of the metal permits considerable relative movement of the sheets.

Obviously, the construction and arrangement of the sheets may be modified considerably without departing from the invention. Therefore, I do not wish to be limited to any specific construction and arrangement shown.

What I claim is:

1. A sheet for car roofs having one of its marginal portions flanged upward and rebent inward and downward, said flanged up and rebent portions being spaced apart, its opposite marginal portion being flanged upward and rebent outward and downward, said last-mentioned flanged up and rebent portions being spaced farther apart than those at opposite side of the sheet, the second-mentioned marginal portion of the sheet beyond the downturned portion being formed to provide an upstanding tongue in the space between said downturned portion and the adjacent flanged up portion, the free marginal portion of said tongue lying close to said downturned portion and having its extremity bent toward said flanged up portion in the bend connecting said downturned portion with said flanged up portion.

2. A sheet for car roofs having one of its marginal portions flanged upward and rebent inward and downward, said flanged up and rebent portions being spaced apart, its opposite marginal portion being flanged upward and rebent outward and downward,

- 5 said last-mentioned flanged up and rebent portions being spaced farther apart than those at the opposite side of the sheet, the second-mentioned marginal portion of the sheet beyond the downturned portion being formed to provide an upstanding tongue between said downturned portion and the adjacent flanged up portion, the marginal portion of said tongue lying close to said downturned portion and the bend connecting it with said flanged up portion, its highest point being above the highest point of the bend between the flanged up and downturned portions at the opposite side of the sheet, and a lip extending outward and at a downward inclination from under said downturned portion and terminating in a plane not higher than 70 the body of the sheet.
- 10 3. A sheet for car roofs having one of its marginal portions flanged upward and rebent inward and downward, said flanged up and downturned portions being spaced apart, 75 and the edge of said downturned portion terminating short of the body portion, the opposite marginal portion of the sheet being flanged upward and rebent outward and downward, said last-mentioned flanged up 80 and downturned portions being spaced farther apart than those at the opposite side of the sheet and the bend between said flanged up and downturned portions being at a higher elevation than the corresponding 85 bend at said opposite side of the sheet, said last-mentioned downturned portion terminating above the body of the sheet, but lower than the edge of said downturned portion at the opposite side of the sheet, the marginal 90 portion of the sheet beyond said last-mentioned downturned portion being formed to provide an upstanding tongue between said downturned portion and the adjacent flanged up portion, the marginal portion of said 95 tongue lying close to said downturned portion and the bend connecting it with said flanged up portion, its highest point being above the highest point of the bend between the flanged up and downturned portions at the 100 opposite side of the sheet.
- 15 4. A sheet for car roofs having one of its marginal portions flanged upward and rebent inward and downward, said flanged up and downturned portions being spaced apart, 105 and the edge of said downturned portion terminating short of the body portion, the opposite marginal portion of the sheet being flanged upward and rebent outward and downward, said last-mentioned flanged up portion, the marginal portion of said 110 tongue lying close to said downturned portion and the bend connecting it with said flanged up portion, its highest point being above the highest point of the bend between the flanged up and downturned portions at the 115 opposite side of the sheet.
- 20 5. A roof sheet having one of its side marginal portions flanged upward and then rebent inward and downward, the edge of said downturned portion terminating short of the body portion, the opposite side marginal portion of the sheet being flanged upward and then rebent outward and downward and again rebent inward and upward from a plane below the edge of the first-mentioned downturned marginal portion of the sheet to provide an upstanding tongue, 90 the free edge portion of said tongue lying close to the adjacent downturned portion of the sheet, and the lower portion of said tongue being spaced therefrom.
- 25 6. A roof sheet having one of its side marginal portions flanged upward and then rebent inward and downward, the edge of said downturned portion terminating short of the body portion, the opposite side marginal portion of the sheet being flanged upward and then rebent outward and downward and again rebent inward and upward from a plane below the edge of the first-mentioned downturned marginal portion of the sheet and then back upon the inner side of said 100 last-mentioned upturned portion to provide a tongue whose free edge portion lies close to the adjacent downturned portion of the sheet, the extreme marginal portion of the sheet extending out from under said last-mentioned downturned portion and terminating in a plane not higher than the body of the sheet.
- 30 7. A roof sheet having one of its side marginal portions flanged upward and then rebent inward and downward, the edge of said downturned portion terminating short of the body portion, the opposite side marginal portion of the sheet being flanged upward and then rebent outward and downward, the upper bend occurring in a plane higher than that of the corresponding bend at the opposite side of the sheet, and again rebent inward and upward, the last bend being in a plane lower than the 120 edge of the downturned portion at the opposite side of the sheet, said last-mentioned upturned portion terminating close to the bend which connects the adjacent flanged up portion and downturned portion 125 130
- 35
- 40
- 45
- 50
- 55
- 60
- 65

- and also in a plane above the upper bend at the opposite side of the sheet.
8. A roof sheet having one of its side marginal portions flanged upward and then rebent inward and downward, the edge of said downturned portion terminating short of the body portion, the opposite side marginal portion of the sheet being flanged upward and then rebent outward and downward, the upper bend occurring in a plane higher than that of the corresponding bend at the opposite side of the sheet, and again rebent inward and upward, the last bend being in a plane lower than the edge of the downturned portion at the opposite side of the sheet, said last-mentioned upturned portion terminating close to the bend which connects the adjacent flanged-up portion and downturned portion and also in a plane above the upper bend at the opposite side of the sheet, said sheet being bent down against the inner face of said last-mentioned upstanding portion and the extreme marginal portion of the sheet extending outward thereunder at an inclination and terminating in a plane not higher than the body of the sheet.
9. In a car roof, adjoining metal sheets having upstanding flanges along their contiguous margins, said flanges being rebent and interlocked to form yielding waterproof seams, the marginal flange of the one sheet being bent inward and downward and terminating short of the body of the sheet, said flanged up and downturned portions being spaced apart, and the flange of the adjoining sheet being bent outward and downward over said flanged up and downturned portions of said first-mentioned sheet, and being further formed to provide an upstanding tongue under said downturned portion of said first-mentioned sheet, the marginal portion of said tongue being arranged and adapted to hold the adjoining sheets in the region of the bends connecting the flanged up and downturned marginal portions in close relation, the coöperating marginal portions of the sheets being otherwise spaced to permit relative movement of the sheets.
10. In a car roof, adjoining metal sheets having upstanding flanges along their contiguous margins, said flanges being rebent and interlocked to form yielding waterproof seams, the marginal flange of the one sheet being bent inward and downward and terminating short of the body of the sheet, said flanged up and downturned portions being spaced apart, and the flange of the adjoining sheet being bent outward and downward over said flanged up and downturned portions of said first-mentioned sheet, and being further formed to provide an upstanding tongue under said downturned portion of said first-mentioned sheet, the marginal portion of said tongue being arranged and adapted to hold the adjoining sheets in the region of the bends connecting the flanged up and downturned marginal portions in close relation, the coöperating marginal portions of the sheets being otherwise spaced to permit relative movement of the sheets.
11. In a car roof, adjoining metal sheets having upstanding flanges along their contiguous margins, said flanges being rebent and interlocked to form yielding waterproof seams, the marginal flange of the one sheet being bent inward and downward and terminating short of the body of the sheet, said flanged up and downturned portions being spaced apart, and the flange of the adjoining sheet being bent outward and downward over said flanged up and downturned portions of said first-mentioned sheet, and being further formed to provide an upstanding tongue under said downturned portion of said first-mentioned sheet, the marginal portion of said tongue being arranged and adapted to support the adjoining sheet in the region of the bend connecting its flanged up and downturned marginal portion and also hold the adjacent portions of the two sheets in close relation, and a lip extending out from under said tongue and adjacent downturned portion and bearing upon the adjacent body portion of the adjoining sheet, the coöperating marginal portions of the sheets being otherwise spaced to permit relative movement of the sheets.
12. In a car roof, interlocking roof sheets, one of said sheets having its side marginal portion flanged upward and then rebent inward and downward, the edge of said downturned portion terminating short of the body portion of said sheet, said flanged up and downturned portions being spaced apart, the second sheet having its side marginal portion flanged upward and then rebent outward and downward, said flanged up and downturned portions of said second sheet being spaced farther apart than the flanged up and downturned portions of the first sheet, said marginal portion of the second sheet being again rebent inward and upward from a plane below the edge of the downturned marginal portion of the first sheet to provide an upstanding tongue, said tongue being spaced from the adjacent downturned portion of the first sheet in the region of the bend which connects said tongue to the downturned portion of the second sheet, and the free edge portion of said tongue lying close to the adjacent portion of the first sheet.
13. A roof sheet having one of its side marginal portions flanged upward and then rebent inward and downward, the edge of

- said downturned portion terminating short of the body portion, said flanged up and downturned portions being spaced apart, the opposite side marginal portion of the sheet 5 being flanged upward and then rebent outward and downward, said last-mentioned flanged up and downturned portions being spaced farther apart than said first-mentioned flanged up and downturned portions, 10 said second-mentioned marginal portion of the sheet being again rebent inward and upward from a plane below the edge of said first-mentioned downturned marginal portion and then back upon the inner side of 15 said last-mentioned upturned portion to provide an upstanding tongue, said tongue being spaced from the adjacent downturned portion of the sheet in the region of the bend which connects it thereto and the free 20 edge portion of said tongue lying close to said adjacent downturned portion, and the extreme marginal portion of the sheet extending outward and terminating in a plane not higher than the body of the sheet. 25 14. A car roof comprising a multiplicity of adjoining metal sheets connected by upstanding waterproof seams, said seams being formed by flanging the marginal portion of the one sheet upward and then rebending it inward and downward, the edge 30 of the sheet terminating short of the body portion, and flanging upward the adjacent marginal portion of the adjoining sheet and then rebending it outward and downward, 35 and again rebending it upward from a plane below the edge of the downturned portion of said first-mentioned sheet to provide an upstanding tongue, and the free edge portion of said tongue lying close to the adjacent 40 downturned portion of its sheet with its extremity extending part way around the bend toward the flanged up portion, the downturned marginal portion of said first-mentioned sheet being inserted between said 45 tongue and the adjacent downturned portion of said second-mentioned sheet. 50 15. A car roof comprising a multiplicity of adjoining metal sheets connected by upstanding waterproof seams, said seams: being formed by flanging the marginal portion of the one sheet upward and then rebending it inward and downward, the edge 55 of the sheet terminating short of the body portion, and flanging upward the adjacent marginal portion of the adjoining sheet and then rebending it outward and downward, and again rebending it upward from a plane below the edge of the downturned portion of said first-mentioned sheet and then 60 back upon the inner side of said last-mentioned upturned portion to provide an upstanding tongue, the free marginal portion of said tongue lying close to the adjacent downturned portion of its sheet, 65 and the extreme marginal portion of said second-mentioned sheet extending outward and terminating in a plane not higher than the body of the sheet so as to bear upon the top of the adjoining sheet, the downturned marginal portion of said first-mentioned sheet being inserted between said upstanding tongue and downturned adjacent portion of the other sheet. 70 16. In a metal covering for car roofs, a flexible joint comprising interlocked flanges, 75 one of said flanges being bent up from the roof covering and having its upper margin turned inwardly and terminating in a downturned lip spaced above said roof covering, the other of said interlocked flanges covering said first flange and having its margin doubled back upon itself and the doubled portion hooked under said lip with its free edge projecting from under said lip and in contact with said roof covering, the fit 80 of said flanges maintaining said free edge in contact with said roof covering. 17. In a metal covering for car roofs, a flexible joint comprising an under flange and a cover flange interlocked therewith, said 85 under flange having an upright portion supported from the roof covering with its upper edge bent over the roof covering and terminating in a downturned lip, and said cover flange having a portion covering said 90 under flange and terminating in contact with said roof covering adjacent to said lip, an intermediate portion of said cover flange being doubled under said lip, the extremity of said doubled portion being turned up against 95 the under side of the turned over edge of said under flange, whereby said flanges are maintained in close contact at two points along their under sides throughout their 100 length. 105 18. A sheet for car roofs having one of its marginal portions flanged upward and rebent inward and downward, said flanged up and rebent portions being spaced apart, its opposite marginal portion being flanged upward and rebent outward and downward, said last-mentioned flanged up and rebent portions being spaced farther apart than those at the opposite side of the sheet, the second-mentioned marginal portion of the 110 sheet beyond the downturned portion being folded under said downturned portion to provide an inturned tongue below said downturned portion and extending toward said flanged up portion, and a lip extending 115 outward from under said tongue and adjacent downturned portion and terminating in a plane not higher than the body of the sheet. 120 19. In a metal covering for car roofs, a 125 flexible joint comprising an under flange and a cover flange interlocked therewith, said under flange having an upright portion sup-

ported from the roof covering with its upper edge bent over the roof covering and terminating in a downturned lip, and said cover flange having a portion covering said under flange and terminating in contact with said roof covering adjacent to said lip, an intermediate portion of said cover flange being doubled under said lip, and having its extremity turned up, whereby said flanges

are maintained in close contact throughout 10 their length.

Signed at St. Louis, Mo., this 26th day of April, 1913.

JOHN J. HOFFMAN.
